[57] CLAIM

The ornamental design for a tissue holder, as shown and described.

DESCRIPTION

FIG. 1 is a perspective view of the tissue holder showing our new design;

FIG. 2 is a front elevational view thereof;

FIG. 3 is a left side elevational view thereof, the right side being a mirror image of that shown;

FIG. 4 is a top plan view thereof, the bottom being a mirror image of that shown;

FIG. 5 is a rear elevational view thereof;

FIG. 6 is a perspective view of an alternate embodiment thereof;

FIG. 7 is a front elevational view of the embodiment of FIG. 7;

FIG. 8 is a left side elevational view of the embodiment of FIG. 7, the right side being a mirror image of that shown;

FIG. 9 is a top plan view of the embodiment of FIG. 7, the bottom being a mirror image of that shown; and FIG. 10 is a rear elevational view of the embodiment of FIG. 7.

The broken-line showing of the frame insert in FIG. 1 is for illustrative purposes only and forms no part of the claimed design.

FIG-1-FIG-2-FIG-3-FIG-4-FIG-5-FIG-6-FIG-7-FIG-8-FIG-9-FIG-10-UNITED STATES PATENT AND TRADEMARK OFFICE
CERTIFICATE OF CORRECTION

PATENT NO. : Des. 302,223

DATED : July 18, 1989

INVENTOR(S) : Michael S. Joss; Stanley T. Gresens; Richard Fraker

It is certified that error appears in the above-identified patent and that said Letters Patent is hereby corrected as shown below:

Change the title from "TISSUE HOLDER" to --BATHROOM FRAME FIXTURE--.

In the Claim, change "tissue holder" to --bathroom frame fixture--.

In the description of Fig. 1, change "tissue holder" to --bathroom frame fixture--.
